THERMALLY RESPONSIVE OVEN BURNER
CONTROL UNIT

Richard L. Perl, Galion, Ohio, assignor to The
Tappan Stove Company, Mansfield, Ohio, a cor-
poration of Ohio

Application May 23, 1951, Serial No. 227,836

23 Claims. (Cl. 200—137)

1

This invention relates to a thermally responsive control unit for use in automatic ignition and control systems for the oven burners of cooking ranges using gaseous fuel, and is an improvement of the control unit disclosed in the co-pending application of Charles M. Mayer, Serial No. 196,659, filed November 20, 1950, and now abandoned. It is especially adapted for use in automatic ignition and control systems in which the main burner is ignited by an associated pilot burner which must burn constantly all of the time the main burner is turned on. The pilot burner is ignited by an electrical resistance ignition element which is automatically de-energized after the pilot burner has been ignited.

In most cooking ranges in use today it is immaterial whether or not the oven burner burns constantly as long as the pilot burner associated therewith is ignited. It may be extinguished for some reason but it will be promptly reignited by the pilot burner if fuel is supplied thereto. But if the pilot burner is extinguished for any reason while the main control valve is still open to supply gas to the main burner a very dangerous situation sometimes arises. Let us assume that both the pilot burner and the main burner are extinguished during operation for some reason. Gas can then flow to the main burner but since the pilot burner is extinguished the main burner will not be ignited and unburned gas will accumulate in the oven which may violently explode when an attempt is made to ignite either the main or pilot burner. It has been found by experience that both the pilot burner and the main burner are frequently extinguished during use while the main control valve is open to supply gas to the main burner. This is sometimes due to a momentary failure of the gas supply or the slamming of the oven door or to various other reasons.

In order to prevent an accumulation of unburned gas and thus eliminate danger of an explosion therefrom in the event the pilot burner is extinguished for any reason while the control valve is still open to supply gas to the main burner, a safety control valve mechanism by which the supply of gas to the main burner is cut off independently of the main control valve, in the event the pilot burner is extinguished for any reason while the main gas control valve is open, is provided.

I have shown my improved control unit incorporated in an automatic ignition and control system which includes a main gaseous fuel

burner by which the oven in a cooking range is heated. The main burner is adapted to be ignited by a gaseous fuel pilot burner which burns only during the time the oven is in operation. At other times the supply of gas to both the main burner and the pilot burner is cut off by a main control valve which is interposed in a conduit between the gas supply manifold and the burners. When the main control valve is open gas will flow from the manifold through the main control valve and into a safety control valve mechanism. From the safety control valve mechanism gas will flow through a small branch conduit directly to the pilot burner; and through the main conduit and a standard thermostatically operated oven temperature control valve to the main burner. A normally open master control switch which is operatively associated with the main control valve is arranged to be closed by the opening of the main control valve and to be opened by the closing of the main control valve. The closing of the master control switch, as the main control valve is opened to supply gas to the burners, makes a circuit which through a normally closed switch in the control unit energizes an electric resistance ignition element and a solenoid which is operatively connected to the safety control valve mechanism. The energization of the solenoid causes it to operate the safety control valve mechanism to permit the flow of gas to the pilot burner while cutting off the supply of gas to the main burner. The pilot burner is then ignited by the electric ignition element and projects a flame against a thermostatic element, in the control unit, which controls the operation of the normally closed switch, and against a thermocouple which is in circuit with an electromagnet in the safety control valve mechanism. After the thermostatic element becomes heated it opens the normally closed switch which de-energizes the electric ignition element and the solenoid. As soon as the solenoid is de-energized the safety control mechanism is automatically operated by spring means to supply gas to the main burner through the oven temperature control valve. The main burner is then ignited by the pilot burner. The thermocouple, as long as it is heated by the pilot burner, maintains the safety control valve mechanism through the electromagnet in condition to supply gas to both the main burner and the pilot burner. The oven temperature control valve then regulates the supply of gas to the main burner so as to maintain the desired oven temperature. As long as

3

the pilot burner is ignited the main burner will burn normally under the control of the oven temperature control valve until the main control valve is manually turned off. But if during operation the pilot burner is extinguished for any reason the thermocouple will immediately cool and de-energize the electromagnet which will allow the safety control valve mechanism to cut off automatically the supply of gas to both the main burner and the pilot burner. As an example of the manner of operation of the apparatus, let us assume that during operation the pilot burner is suddenly extinguished, for instance, by a momentary failure of the gas supply from the manifold to the burners. The thermocouple immediately cools, causing the safety control valve mechanism to cut off communication between the manifold and both the main burner and the pilot burner. The main control valve is still open and the master switch closed. Then after the thermostatic element has cooled, closing the normally closed switch, which is maintained open by the thermostatic element during normal operation of the oven, the electric ignition element and the solenoid are again energized. The energization of the solenoid will cause it to operate the safety control valve mechanism to re-establish communication between the manifold and the pilot burner only. Then when gas is again available the pilot burner will be ignited and re-establish normal operation of the oven as previously described. In the event of a power failure during normal operation of the oven, the main burner will continue to operate normally under the control of the oven temperature regulator valve until the burner is turned off by the main control valve, assuming of course that the pilot burner continues to burn. In the event of a power failure before gas is turned on by the main control valve, the pilot burner can be manually ignited, and the supply of gas to both the main burner and the pilot burner will then be controlled by the pilot burner through the thermocouple and safety control valve mechanism as previously described.

The principal object of the invention is to provide a very simple, efficient and inexpensive thermally responsive unit for use in automatic ignition and control systems for the oven burners of cooking ranges which is not affected by prolonged high ambient temperatures in the oven.

Other and more limited objects of the invention will be apparent from the following specification and the accompanying drawings forming a part thereof wherein:

Fig. 1 is a diagrammatic layout showing my improved control unit incorporated in an automatic ignition and safety control system for an oven burner using gaseous fuel;

Fig. 2 is an enlarged plan view of the control unit;

Fig. 3 is a view in sectional elevation taken on the line 3—3 of Fig. 2;

Fig. 5 is a sectional view taken on the line 5—5 of Fig. 2;

Fig. 6 is a view similar to Fig. 2 showing a modified form of the control unit;

Fig. 7 is a sectional elevation taken on the line 7—7 of Fig. 6;

Fig. 8 is a view similar to Figs. 2 and 6 of still another form of the control unit, and

Fig. 9 is a sectional elevation taken on the line 9—9 of Fig. 8.

4

Referring now to the drawings by reference characters, the numeral 1 indicates a gaseous fuel burner which is mounted in or in heating relation to a cooking range oven 2. Gaseous fuel is supplied to the burner 1 from a manifold M through a conduit 3. Interposed in the conduit 3 are a main control valve 4, a safety control valve mechanism generally indicated by the numeral 5, and an oven temperature control valve 6. The main control valve 4 is a cut-off valve of standard construction which when in open or on position permits the flow of gas through the conduit 3 from the manifold M to the burner 1, and in closed or off position cuts off the flow of gas to the burner 1. This valve is manually opened and closed by a handle 7 and a valve stem 8, and directly controls the operation of the entire system in that it initiates the operation of the entire system when it is turned to the on position and terminates the operation when it is turned to the off position. From the main control valve 4 gas flows through a connector 9 to the safety control valve mechanism 5. From the safety control valve mechanism 5 the gas flows through a connector 10, a standard oven temperature control valve 6 and the conduit 3 to the burner 1. The oven temperature control valve 6 is operative to regulate the amount of gas flowing to the burner 1 in order to maintain the oven at any desired set temperature. The valve 6 which is set to any desired temperature by a handle 11 having a pointer 12 which cooperates with a graduated dial 13 carried by the valve 6 is controlled according to the temperature setting by a thermostatic element 14 which is mounted in the oven 2 and is connected to the valve 6 as shown at 15. Gas is also supplied to a pilot burner 16 through a branch conduit 17 which extends between the safety control valve mechanism 5 and the pilot burner 16. The pilot burner 16 is disposed adjacent one end of the main burner 1 in position to ignite the burner 1 when gas is supplied thereto. An electrical ignition element 18 is operatively associated with the pilot burner 16 in position to ignite the pilot burner 16 when gas is supplied thereto. The pilot burner 16 is mounted upon the control unit 19 in position to heat a thermostatic element 20 incorporated therein and forming a part thereof. A thermocouple 21 is mounted upon the control unit 19 adjacent the pilot burner 16 in position to be heated thereby. The thermostatic element 20 is operative to open and close a switch 22 which controls the energization of the electrical ignition element 18 and a solenoid 23 which when energized operates the safety control valve mechanism 5 through linkage 24 to supply gas to the pilot burner 16. The thermocouple 21 when heated is operative to hold the safety control valve mechanism in condition to maintain the supply of gas to both the pilot burner 16 and the main burner 1. A master switch 25 which is associated with the main control valve 4 is adapted to be opened and closed simultaneously with the closing and opening of the main control valve 4. As the control valve 4 is turned from the off or closed position to the on or opened position the switch 25 is moved from the open position to the closed position by an operating lever 26 which cooperates with a cam section 27 on the main control valve stem 8. Conversely, when the main control valve 4 is turned from the open or on position to the closed or off position the switch 25 is moved from the

closed position to the open position. An electric circuit between the thermocouple 21 and the safety control valve mechanism 5 is established by a copper tube 28 and an enclosed insulated wire. The ignition and control system just described per se constitutes no part of the subject matter of this application but is shown and claimed in the co-pending applications, Serial Nos. 153,664 now Patent No. 2,577,787 and 163,764 now Patent No. 2,578,717, filed April 3, 1950, and May 23, 1950, respectively, by Charles M. Mayer and John M. Hoff.

The control unit 19 which constitutes the subject matter of this application comprises a base 30 having upper and lower horizontal sections 31 and 32 which are connected together by a vertical web 33. The free edge of the lower section 32 is turned downwardly as shown at 34 for stiffening purposes. The base has integral therewith a pair of tabs 35 which are welded to a transverse plate 36 which is secured to an inner wall 37 of the oven 2 by bolts 38. The base 30 extends inwardly from the wall 37 along one side of the burner 1 as shown in Figs. 1 and 2. The normally closed switch 22 comprises a block 39 of insulating material, a stationary contact 40, and a movable contact 41. The stationary contact 40 is held in position in the block 39 by a terminal bolt 42, and the movable contact 41 is carried by the free end of a spring arm 43 which is biased toward the stationary contact 40 and is held in position in the block 39 by a terminal bolt 44. The block 39 is secured by bolts 45 to the under side of a downwardly inclined sheet metal plate 46 which has one end thereof welded to the underside of the lower section 32 of the base as indicated at 47. The free end of the plate 46 is urged downwardly by the inherent resiliency of the plate itself. A rotatable screw 48 which extends downwardly through a vertical bore in the lower section 32 is threaded through an aperture adjacent the free end of the plate 46 and is operative when rotated to adjust the free end of the plate 46 upwardly and downwardly, and with it the switch 22 carried thereby.

The thermostatic element 20 is formed from a single piece of thin sheet metal and comprises a relatively long narrow horizontal section 50 having an upturned section 51 along one edge thereof and a pair of spaced legs 52 and 53 extending downwardly from the other edge thereof. The leg 52 is disposed at one end of the element and the leg 53 is disposed substantially midway between the ends thereof. The legs 52 and 53 terminate in horizontally extending feet 54 and 55 which are spot welded to the top of the lower section 32 of the base 30, as indicated at 56 and 57. An arm 58 extends outwardly from the leg 53 and downwardly from the edge of the horizontal section 50 opposite the upturned section 51, in substantially the plane of the legs 52 and 53, and terminates in a downwardly extending finger 59. The finger 59 extends down through an aperture 60 in the lower section 32 of the base 30 and is adapted to engage an insulating button 61 secured to the spring arm 43 of the switch 22.

The horizontal arm 62 of an angular bracket 63 is welded to the upper section 31 of the base and extends outwardly therefrom. The thermocouple 21 and the pilot burner 16 are rigidly secured to the vertical arm 64 of the bracket 63 by a clamp 65 and bolt 66. The thermocouple 21 is disposed directly above the pilot burner 16

with the ends of both the thermocouple and the pilot burner closely adjacent the upturned section 51 of the thermostatic element. The electric ignition element 18 is mounted at one side of the pilot burner 16 adjacent the end thereof in an insulating block 67 which is fastened to the vertical arm 64 of the bracket 63 by a screw 68. When gas is supplied to the pilot burner 16 it will be ignited by the electric ignition element 18, after which the flame from the pilot burner will impinge upon the section 51 of the thermostatic element 20 and fan out as shown by the line F in Fig. 3, and heat both the thermostatic element 20 and the thermocouple 21. It will also ignite the main burner 1 when gas is supplied thereto.

The localized heating of the thermostatic element between the legs 52 and 53 will cause the element to elongate and rock the arm 58 downwardly about the foot 55 as a pivot. The downward movement of the end of the arm 58 will through the finger 59 depress the spring switch arm 43 and separate the contacts 40 and 41, thus opening the normally closed switch 22. The adjusting screw 48 is provided in order to adjust the relative positions of the lower end of the finger 59 and the spring arm 43 with respect to each other.

In operation it is only necessary to open the main control valve 4 manually which simultaneously closes the normally open master switch 25. The closing of the master switch 25 will through the normally closed switch 22 complete a circuit through and energize the solenoid 23 and the electric ignition element 18. The energizing of the solenoid 23 causes it to set the safety control valve 5 in condition to supply gas to the pilot burner 16 only, which is then ignited by the ignition element 18. After the pilot burner 16 has been ignited it projects a flame against and heats the thermostatic element 20 and the thermocouple 21. The heating of the thermostatic element 20 causes it to open the normally closed switch 22 and break the circuit to and de-energize the solenoid 23 and the ignition element 18; and the heating of the thermocouple 21 renders it operative to maintain the safety control valve mechanism 5 in position to supply gas to the pilot burner, and to the main burner 1 after the solenoid 23 has been de-energized. The de-energizing of the solenoid 23 renders the safety control valve 5 operative also to supply gas to the main burner 1 which is then ignited by the pilot burner 16. After this, under normal conditions, the main burner 1 will operate under control of the oven temperature control valve 6 until operation is terminated by the manual closing of the main control valve 24.

In the event the pilot burner 16 is extinguished for any reason during operation the thermocouple 21 will cool in a few seconds which will cause the safety control valve 5 to cut off the supply of fuel to both the main burner and the pilot burner. The main burner will then be extinguished along with the pilot burner. As soon as the thermostatic element 20 cools it will close the switch 22 which will energize both the ignition element 18 and the solenoid 23 as previously described, since the main control valve 4 is still open and the switch 25 is closed. The pilot burner 16 will then be re-ignited and the rest of the apparatus will again function as described, provided there is gas available. If no gas is available everything will remain in condition to ignite the pilot burner and re-initiate operation

as soon as gas is again available. In the event of either a momentary or prolonged power failure during operation, the apparatus will continue to operate normally until terminated by the manual closing of the main control valve, provided of course that all other conditions are normal. In order to operate the apparatus during a prolonged power failure which occurred prior to operation, it is only necessary to hold a match to the pilot burner 16 and manually hold the safety control valve 5 in position to supply gas to the pilot burner a sufficient time for the thermocouple 20 to become heated. The apparatus will then continue to function normally as described under the control of the pilot burner 16 and the oven temperature control valve 6.

Since the control unit 19 is mounted in the oven 2 adjacent the burner 1, it is subjected to the ambient temperature of the oven which sometimes exceeds 600° Fahrenheit. It has been found by experience that when the unit 19 is subjected to high ambient temperatures for prolonged periods of time, the base 30 of the unit 19 elongates, bends, twists and otherwise distorts; and that this distortion sometimes counteracts the downward movement of the end of the arm 58 and finger 59 effected by the localized heating of the thermostatic element 20 by the pilot burner 16. This counter movement of the arm 58 is principally due to the elongation of the section 32, of the base 30, between the legs 52 and 53 of the thermostatic element. When this condition occurs the switch 22 closes which re-energizes the solenoid 23 and the electric ignition unit 17. The re-energization of the solenoid 23 causes it to operate the safety control valve mechanism to cut off the supply of gas to and extinguish the main burner while continuing the supply of gas to the pilot burner. The solenoid 23 will remain energized, cutting off the supply of gas to the main burner 1 until the temperature in the oven 2 drops and the base 30 of the unit 19 cools sufficiently for the thermostatic element 20, under the influence of the pilot burner 16, to again open the switch 22. The device will then operate as described until the base 30 is again distorted by the ambient temperature sufficiently to counteract the action of the thermostatic element 20. From this it will be seen that under certain conditions it is impossible to maintain a constant temperature in the oven 2. Sometimes the distortion of the base is such that it amplifies the downward movement of the end of the arm 58 and the finger 59 in which case the switch 22 will not close upon the extinguishment of the pilot burner 16 and the cooling of the thermostatic element down to the ambient temperature of the oven, but will remain open until the base 30 cools considerably, which objectionally delays the re-cycling of the apparatus.

In order to overcome this objectionable condition, I provide means on the control unit 19 by which the distortion of the base 30 of the control unit 19 is counteracted and the relative positions of the end of the finger 59 and the switch arm 43 with respect to each other are maintained fixed during all conditions of operation. This means consists of a flat bi-metallic disc 70 which is placed upon the lower section 32 of the base 30, and has the adjusting screw 48 inserted through a medial aperture therein. As the bi-metallic disc 70 is heated by the ambient temperature in the oven 2, the midsection through which the adjusting screw 48 extends will bow upwardly and raise the switch 22 accordingly. The upward

bowing of the bi-metallic disc 70 is concurrent with the distortion of the base 30. Consequently as the arm 58 and finger 59 are moved upwardly by the distortion of the base 30 the switch 22 is likewise moved upwardly by the bowing of the disc 70. Thus after the switch 22 has been opened by the heating of the thermostatic element 20 by the pilot burner 16, the relation between the finger 59 and the spring arm 43 will be maintained fixed and the switch 22 open all during operation, regardless of the ambient temperature within the oven, provided of course that the pilot burner 16 remains ignited.

In Figs. 6 and 7, I have shown a slightly modified form of the control unit 19. In this form of the invention I place a bi-metallic disc 71, similar to the disc 70, under the foot 54 of the leg 52 and weld the foot 54 to the midsection of the disc 71, as indicated at 72. I then weld one edge of the disc 71 to the base 30, as indicated at 73. Otherwise the construction and operation of this form of the invention are the same as those shown in Figs. 1 to 5 and the same reference characters are applied to like parts.

In Figs. 8 and 9, I have shown another modification of the control unit 19. In this form of the invention I place a bi-metallic disc 75, similar to the discs 70 and 71, under the foot 55 of the leg 53 and weld the foot 55 to the disc 75, as indicated at 76, and weld one edge of the disc 75 to the frame 30, as indicated at 77. Otherwise the construction and operation of this form of the invention are the same as those shown in Figs. 1 to 5, and in Figs. 6 and 7, and the same reference characters are applied to like parts.

In order to counteract the amplified opening of the switch 22 due to the distortion of the base 30, I construct the bi-metallic discs 70, 71 and 75 so that they are arcuate when cool and flat when heated.

From the foregoing it will be apparent to those skilled in this art that I have provided a very simple and efficient means for accomplishing the objects of my invention; and it is to be understood that I am not limited to the specific constructions shown and described herein as various modifications may be made thereto within the scope of the appended claims.

What is claimed is:

1. A thermally responsive control unit for a gaseous fuel oven burner comprising a base adapted to be mounted in a cooking range oven subject to the ambient temperature therein, a downwardly inclined resilient plate having the upper end thereof rigidly secured to the under side of said base, an electric switch having an open and a closed position carried by said plate, a thermostatic element secured to the upper side of said base and operative when heated by a pilot burner flame impinging thereon to shift said switch from one position to the other position, and means to raise and lower the free end of said plate and thereby adjust the position of said switch relative to said thermostatic element.
2. A thermally responsive control unit for a gaseous fuel oven burner comprising a base adapted to be mounted in a cooking range oven subject to the ambient temperature therein, an electric switch having an open and a closed position, a thermostatic element mounted upon said base, interengageable means between said switch and said thermostatic element, said thermostatic element when heated by a pilot burner flame impinging thereon flexing sufficiently to shift said switch through said interengageable means from

one position to the other, said base being distortable by the ambient temperature in the oven in a direction to counteract the flexing action of said thermostatic element, and thermally responsive means incorporated in said control unit and operative to counteract the distortion of said base.

3. A thermally responsive control unit as defined in claim 2 in which said thermally responsive means comprises a bi-metallic disc and operative connections between said bi-metallic disc and said switch through which said bi-metallic disc moves said switch in accordance with the distortion of said base to maintain the relative positions of said switch and said thermostatic element with respect to each other fixed during operation of the oven burner.

4. A thermally responsive control unit for a gaseous fuel oven burner comprising a base adapted to be mounted in a cooking range oven subject to the ambient temperature therein, a downwardly inclined resilient plate having the upper end thereof rigidly secured to the under side of said base, an electric switch having an open and a closed position carried by said plate, a thermostatic element secured to the upper side of said base, interengageable means between said switch and said thermostatic element, said thermostatic element when heated by a pilot burner flame impinging thereon flexing sufficiently to shift said switch through said interengageable means from one position to the other, adjusting means by which the free end of said plate is raised and lowered to adjust the position of said switch relative to said thermostatic element, said base being distortable by the ambient temperature in said oven in a direction to counteract the flexing action of said thermostatic element, and thermally responsive means incorporated in said control unit and operative to counteract the distorting movement of said base.

5. A thermally responsive control unit as defined in claim 4 in which said thermally responsive means comprises a bi-metallic disc and operative connections between said bi-metallic disc and said adjusting means through which said bi-metallic disc raises the free end of said plate in accordance with the distortion of said base to maintain the relative positions of said switch and said thermostatic element with respect to each other fixed during operation of the oven burner.

6. A thermally responsive control unit for a gaseous fuel oven burner comprising a base adapted to be mounted in a cooking range oven subject to the ambient temperature therein, a downwardly inclined resilient plate having the upper end thereof rigidly secured to the under side of said base, an electric switch having an open and a closed position carried by said plate, a thermostatic element secured to the upper side of said base, interengageable means between said switch and said thermostatic element, said thermostatic element when heated by a pilot burner flame impinging thereon flexing sufficiently to shift said switch through said interengageable means from one position to the other, a screw rotatably mounted in an aperture in said base and extending downwardly through a threaded aperture in said plate and having a head on the upper end thereof, said screw being operative to raise and lower the free end of said plate to adjust the position of said switch relative to said thermostatic element, said base being distortable by the ambient temperature in said oven in a

direction to counteract the flexing action of said thermostatic element, and thermally responsive means incorporated in said control unit and operative to counteract the distorting movement of said base.

7. A thermally responsive control unit as defined in claim 6 in which said thermally responsive means comprises a bi-metallic disc interposed between said screw head and the top of said base and operative to raise said screw and said plate in accordance with the distortion of said base to maintain the relative position of said switch and said thermostatic element with respect to each other fixed during operation of the oven burner.

8. A thermally responsive control unit for a gaseous fuel oven burner comprising a base adapted to be mounted in a cooking range oven subject to the ambient temperature therein, a downwardly inclined resilient plate having the upper end thereof rigidly secured to the under side of said base, an electric switch having an open and a closed position carried by said plate, a thermostatic element having two spaced downwardly extending legs the lower ends of which are rigidly secured to the upper side of said base, interengageable means between said switch and said thermostatic element, said thermostatic element when heated by a pilot burner flame impinging thereon flexing sufficiently to shift said switch through said interengageable means from one position to the other, a screw rotatably mounted in an aperture in said base and extending downwardly through a threaded aperture in said plate and having a head on the upper end thereof, said screw being operative to raise and lower the free end of said plate to adjust the position of said switch relative to said thermostatic element, said base being distortable by the ambient temperature in said oven in a direction to counteract the flexing action of said thermostatic element, and thermally responsive means incorporated in said control unit and operative to counteract the distorting movement of said base.

9. A thermally responsive control unit as defined in claim 8 in which said thermally responsive means comprises a bi-metallic disc interposed between said screw head and the top of said base and operative to raise said screw and said plate in accordance with the distortion of said base to maintain the relative positions of said switch and said thermostatic element with respect to each other fixed during operation of the oven burner.

10. A thermally responsive control unit for a gaseous fuel oven burner comprising a base adapted to be mounted in a cooking range oven subject to the ambient temperature therein, an electric switch having an open and a closed position, a thermostatic element having two spaced downwardly extending legs the lower end of at least one of which is rigidly secured directly to said base, interengageable means between said thermostatic element and said switch, said thermostatic element when heated by a pilot burner flame impinging thereon flexing sufficiently to shift said switch through said interengageable means from one position to the other, said base being distortable by the ambient temperature in said oven in a direction to counteract the flexing action of said thermostatic element, and thermally responsive means incorporated in said control unit and operative to counteract the distorting movement of said base.

11. A thermally responsive control unit as defined in claim 10 in which said thermally responsive means comprises a bi-metallic disc interposed between one of said legs and said base, said bi-metallic disc being rigidly secured to said base and to said one of said legs and operative to move said switch in accordance with the distortion of said base to maintain the positions of said switch and said thermostatic element with respect to each other fixed during operation of said oven 10 burner.

12. A thermally responsive control unit for a gaseous fuel oven burner comprising a base adapted to be mounted in a cooking range oven subject to the ambient temperature therein, an electric switch having an open and a closed position, a thermostatic element having a downwardly extending medial leg and a spaced downwardly extending end leg the lower end of which is rigidly secured to said base, interengageable means between said thermostatic element and said switch, said thermostatic element when heated by a pilot burner flame impinging thereon flexing sufficiently to shift said switch through said interengageable means from one position to the other, said base being distortable by the ambient temperature in said oven in a direction to counteract the flexing action of said thermostatic element, and thermally responsive means incorporated in said control unit and operative to counteract the distorting movement of said base. 15

13. A thermally responsive control unit as defined in claim 12 in which said thermally responsive means comprises a bi-metallic disc interposed between said medial leg and said base, said bi-metallic disc being rigidly secured to said base and said medial leg and operative to move said switch in accordance with the distortion of said base to maintain the positions of said switch and said thermostatic element with respect to each other fixed during operation of said oven burner.

14. A thermally responsive control unit for a gaseous fuel oven burner comprising a base adapted to be mounted in a cooking range oven subject to the ambient temperature therein, an electric switch having an open and a closed position, a thermostatic element having a downwardly extending end leg and a spaced downwardly extending medial leg the lower end of which is rigidly secured to said base, interengageable means between said thermostatic element and said switch, said thermostatic element when heated by a pilot burner flame impinging thereon flexing sufficiently to shift said switch through said interengageable means from one position to the other, said base being distortable by the ambient temperature in said oven in a direction to counteract the flexing action of said thermostatic element, and thermally responsive means incorporated in said control unit and operative to counteract the distorting movement of said base. 20

15. A thermally responsive control unit as defined in claim 14 in which said thermally responsive means comprises a bi-metallic disc interposed between said end leg and said base, said bi-metallic disc being rigidly secured to said base and said end leg and operative to move said switch in accordance with the distortion of said base to maintain the positions of said switch and said thermostatic element with respect to each other fixed during operation of said oven burner. 25

16. A thermally responsive control unit for a gaseous fuel oven burner comprising a base adapted to be mounted in a cooking range oven subject to the ambient temperature therein, an 30

12

electric switch carried by said base, a thermostatic element mounted upon said base, interengageable means between said switch and said thermostatic element, said thermostatic element when heated by a pilot burner flame impinging thereon flexing sufficiently to actuate said switch through said interengageable means, said base being distortable by the ambient temperature in the oven in a direction to change the actuating effect of said thermostatic element on said switch, and thermally responsive means incorporated in said control unit and operative to counteract the distorting movement of said base. 35

17. A thermally responsive control unit as defined in claim 16 in which said thermally responsive means comprises a bi-metallic disc and operative connections between said bi-metallic disc and said switch through which said bi-metallic disc moves said switch in accordance with the distortion of said base to maintain the relative positions of said switch and said thermostatic element with respect to each other fixed during operation of the oven burner. 40

18. A thermally responsive control unit for a gaseous fuel oven burner comprising a base adapted to be mounted in a cooking range oven subject to the ambient temperature therein, a downwardly inclined resilient plate having the upper end thereof rigidly secured to the under side of said base, an electric switch carried by said plate, a thermostatic element secured to the upper side of said base, interengageable means between said switch and said thermostatic element, said thermostatic element when heated by a pilot burner flame impinging thereon flexing sufficiently to actuate said switch through said interengageable means, adjusting means by which the free end of said plate is raised and lowered to adjust the position of said switch relative to said thermostatic element, said base being distortable by the ambient temperature in said oven in a direction to change the actuating effect of said thermostatic element on said switch, and thermally responsive means incorporated in said control unit and operative to counteract the distorting movement of said base. 45

19. A thermally responsive control unit as defined in claim 18 in which said thermally responsive means comprises a bi-metallic disc and operative connections between said bi-metallic disc and said adjusting means through which said bi-metallic disc moves the free end of said plate in accordance with the distortion of said base to maintain the relative positions of said switch and said thermostatic element with respect to each other fixed during operation of the oven burner. 50

20. A thermally responsive control unit for a gaseous fuel oven burner comprising a base adapted to be mounted in a cooking range oven subject to the ambient temperature therein, an electric switch carried by said base, a thermostatic element mounted upon said base, interengageable means between said switch and said thermostatic element, said thermostatic element when heated by a pilot burner flame impinging thereon flexing sufficiently to open said switch through said interengageable means, said base being distortable by the ambient temperature in the oven in a direction to amplify the opening of said switch, and thermally responsive means incorporated in said control unit and operative to counteract the distorting action of said base. 55

21. A thermally responsive control unit as defined in claim 20 in which said thermally respon-

13

sive means comprises a bi-metallic disc and operative connections between said bi-metallic disc and said switch through which said bi-metallic disc moves said switch in accordance with the distortion of said base to maintain the relative positions of said switch and said thermostatic element with respect to each other fixed during operation of the oven burner.

22. A thermally responsive control unit for a gaseous fuel oven burner comprising a base adapted to be mounted in a cooking range oven subject to the ambient temperature therein, a downwardly inclined resilient plate having the upper end thereof rigidly secured to the under side of said base, an electric switch carried by said plate, a thermostatic element secured to the upper side of said base, interengageable means between said switch and said thermostatic element, said thermostatic element when heated by a pilot burner flame impinging thereon flexing sufficiently to open said switch through said interengageable means, adjusting means by which the free end of said plate is raised and lowered to adjust the position of said switch relative to said thermostatic element, said base being distortable by the ambient tempera-

ture in said oven in a direction to amplify the opening of said switch, and thermally responsive means incorporated in said control unit and operative to counteract the distorting movement of said base.

23. A thermally responsive control unit as defined in claim 22 in which said thermally responsive means comprises a bi-metallic disc and operative connections between said bi-metallic disc and said adjusting means through which said bi-metallic disc moves the free end of said plate in accordance with the distortion of said base to maintain the relative positions of said switch and said thermostatic element with respect to each other fixed during operation of the oven burner.
